UNITED STATES PATENT OFFICE.

WALKER J. BOUDWIN, OF SALT LAKE CITY, UTAH, ASSIGNOR TO THE GENERAL ENGINEERING COMPANY, OF SALT LAKE CITY, UTAH, A CORPORATION OF UTAH.

CLASSIFIER AND DEWATERER.

1,201,014.

Specification of Letters Patent. Patented Oct. 10, 1916.

Application filed July 22, 1916. Serial No. 110,683.

To all whom it may concern:

Be it known that I, WALKER J. BOUDWIN, a citizen of the United States, residing at Salt Lake City, in the county of Salt Lake 5 and State of Utah, have invented certain new and useful Improvements in Classifiers and Dewaterers, of which the following is a specification.

My invention relates to an apparatus 10 designed primarily for dewatering sands and slimes of ore wherein the metalliferous particles are progressively fed up an inclined submerged surface, and out of the water onto an appropriate unsubmerged draining surface; 15 and my invention consists of the parts and the constructions, arrangements and combinations of parts which I will hereinafter describe and claim.

In the accompanying drawing forming 20 part of this specification and in which similar reference characters indicate like parts in the several views, Figure 1 is a vertical cross-sectional view of an apparatus constructed according to my invention. Fig. 2 is a top 25 plan view with the superstructure or framework omitted. Fig. 3 is a top plan view of the cone with the flights removed. Fig. 4 is an enlarged cross-sectional view on the line 4-4 of Fig. 2. Fig. 5 is a view similar to 30 Fig. 1, showing the apparatus provided with a froth-retaining hood and showing the apparatus designed as a defrother for flotation or other concentrates. Fig. 6 is an enlarged 35 sectional view of an edge portion of a porous bottom for the pan.

In a prior Patent Number 1,140,793, dated May 25, 1915, I have illustrated and described a classifier and dewaterer having for its essential purposes the classification, washing, mixing and dewatering of sands and slimes of ore and wherein means are provided for advancing the ore upwardly over a submerged inclined surface and out of the water and onto an appropriate unsubmerged 45 draining portion of said surface. The present invention is related to the type of apparatus shown in the said prior patent, and such apparatus is employed in the present instance in order that the improvements may 50 be better understood and appreciated, the leading feature of the said improvement being the application to the conical portion of the prior patented construction, or its equivalent, of a bottom provided with some appropriate porous or filter medium and an un-

derlying vacuum chamber or chambers whereby the liquid contents of the pan may be drawn through said bottom and the separated solid constituents, ore particles and the like of the pulp or slimes may be progressively advanced upwardly over the inclined surface and onto an unsubmerged portion thereof and, finally, be delivered to a central discharge. 80

In the type of apparatus shown, I mount upon a suitable foundation, or framework, a pan-like structure, which comprises a truncated cone, A, the base portion of which is turned at a suitable angle to form a rim and an annular trough, or gutter, B, said upturned portion of the rim being provided with a suitable launder into which the overflow from the pan may be received, said overflow being in a plane below the plane of the apical portion of the cone, and having a vertical wall acting as an overflow or weir which communicates with the said launder. 65 70 75

At the apex or central portion of the cone there is provided an opening through which the ore particles which are advanced up the inclined sides of the cone in the manner I will hereinafter describe and as disclosed in my aforesaid prior patent, may be discharged, said opening communicating with a vertical pipe, D, below the lower or discharge end of which is a suitable belt or other conveyor, I. 80 85

Mounted vertically in a line with the apex of the cone, is a shaft, F, and concentric with this shaft is a second shaft, F', the lower portions of said shafts having connected to them the series of downwardly converging arms, a and b, provided with appropriate curved flights, c, c', respectively, the construction and arrangement of which may follow more or less closely the similar flights or rabbles of my former patent, or they may be of any appropriate and well known character. The two sets of arms operate over different portions of the cone, the uppermost and longest arm having its flights operating over the submerged portion of the cone and the flights of the other and shorter series of arms having its flights operating over the upper and unsubmerged portion of the cone. 95 100 105 The shaft to which the longer arms are secured, is operated at a comparatively low speed and adapted to progressively move the ore particles slowly over the submerged portion of the cone, while the other set of arms 110

is designed to travel at a higher speed and to move the ore particles more quickly over the unsubmerged portion of the cone and to finally discharge these into the central outlet. Any well known form of operating means may be employed for giving this variable rotation to the arms, and in Fig. 1, I illustrate as one means for accomplishing this purpose, a driven pulley, 10, the shaft of which carries a pinion, 11, which drives a large gear, 12, on the shaft to which the longer and slower moving sets of arms are secured. A suitable cross belt, 13, or other connection drives a pulley, 14, or equivalent gear, the shaft of which is provided with a beveled pinion, 15, which meshes with a beveled gear, 16, on the shaft to which the other set of arms, namely, the shorter and fast moving arms are secured. These arms are also shown as supporting an annular feed trough, J, as in the prior patented construction, but manifestly any other type of feeding device may be substituted therefor, if desired.

25 In the present instance, instead of making the bottom of the pan, or more properly speaking, the cone, A, solid and impervious, I now form this bottom of some appropriate permeable material, as canvas, or such other porous material as will permit the liquid constituents of the pulp to filter therethrough. To assist this action and produce a positive filtering function, I form in the cone underlying the fibrous or other filtering surface, a vacuum chamber or chambers, 16', which chambers extend substantially throughout the entire area of the cone, and are connected to valve-controlled branches, 17, to an appropriate pipe, 18, which may 40 lead to a vacuum pump or other suction or exhausting device, not shown, and the function of which is to create a suction beneath the permeable or filtering bottom of the cone to thereby draw therethrough the liquid constituents of the pulp being treated while the coarser sands or metalliferous particles will be retained in a submerged condition on the inclined filter surface and will be progressively advanced upward over the same and 45 out of the water and onto the unsubmerged or draining portion of the cone and finally be delivered into the discharge passage.

The specific construction of the porous bottom of the pan, or the upper surface of the cone portion thereof, is immaterial. In the drawings I show a filtering cloth for the top surface and I support this cloth on appropriate spreaders, 20, which form a backing for the cloth, and I subdivide the air or 55 vacuum chamber into compartments by means of partitions, 21, or otherwise, to each of which compartments one of the branches of the suction pipe, leads. Also, in order to make a tight joint between the bottom 60 end of the cone and the adjacent impervious

wall of the gutter which surrounds the base of the cone, I may use any well known form of packing, 22. The filtering surface of the cone may be made up of a number of sections, 23, of segmental form, as illustrated in Fig. 3, to facilitate the removal and replacement of any one or more of the sections and each of these sections may be composed of canvas or other filtering material having an interior woven wire or other plate, 24, which serves as a backing and stiffener for the filtering bottom.

In Fig. 5, I show the foregoing improvements in connection with a stationary hood, 25, which encircles the upper portion of the cone and which would be used for receiving froth from an appropriate frothing machine, various types of which are now used in connection with the so-called buoyant processes of saving mineral particles.

The hood connects with suitable feed pipes, 26, and the froth delivered thereto and within an annular channel, 27, surrounding the hood, may be received upon a wooden or other float, 28, which is supported upon the surface of the water in the pan, the froth overflowing a vertical flange, 29, which forms the inner wall of the gutter and being directed toward the upper and unsubmerged portion of the cone, and as this portion of the cone has an underlying suction chamber, it will be apparent that the action of the air in passing through the overlying filter surface will tend to break down and destroy the bubbles and liberate the liquid content thereof which will be drawn through the filtering surface and into the suction pipe, as before described, while the liberated concentrates will be advanced upwardly over the upper portion of the cone and into the central discharge.

In practice, and disregarding at the present time the manner in which the material might be fed to the pan, as also the character of said material, the action of the suction devices is to draw fluid matter through the permeable bottom while the solid particles, of whatever character, are deposited on said bottom and are progressively advanced thereover in an upward direction, these particles being moved at low speed while being carried over the submerged portion of the cone and at a high speed while being carried over the unsubmerged upper portion of the cone, this progression of the particles being effected by the flights, rabbles, or other devices fixed to and movable with the arms, before mentioned, and the operation of which parts is similar to that described in the prior patent mentioned. In order that the pores of the filtering medium may be relieved of obstructing matter and the surface of the filter thus renewed or cleaned, I may connect with the suction pipe a valve-controlled branch, 30, through which

compressed air may be admitted under pressure into the several vacuum chambers to operate as a reverse current for the purpose mentioned.

5. Having thus described my invention what I claim as new and desire to secure by Letters Patent is:

1. The combination of a pan having a conical portion and a surrounding gutter at 10 the base thereof, said conical portion being porous to permit the passage of liquid and said pan having a liquid overflow arranged in a plane below the plane of the apical portion of the pan; means for applying a 15 suction to the underside of the porous portion of the pan; and means for progressively moving sands and slimes upwardly over the porous surface of the pan and onto and over an unsubmerged portion thereof.

20. 2. The combination of a pan having a conical portion and a surrounding gutter at the base thereof, said conical portion being porous to permit the passage of liquid and said pan having a peripheral overflow and 25 a central discharge, and having a suction chamber underlying the porous portion; said central portion of the pan projecting above the plane of the pulp level of the pan and being unsubmerged, and said suction chamber 30 extending under the unsubmerged central portion of the pan, and means for progressively moving sands and slimes upwardly over the porous surface of the pan and onto and over the unsubmerged portion 35 thereof.

3. The combination of a pan having a conical portion and an upturned rim forming a gutter at the base thereof, said conical portion being permeable and having an underlying suction chamber, and members operating over the permeable conical surface of the pan having means for progressively moving sands and slimes upwardly over said surface and over an unsubmerged portion 45 thereof, said pan having means for discharging solids at its apex and having an overflow lying in a plane below the plane of the apical portion of the pan.

4. The combination in a pan, having a 50 conical portion and an upturned rim forming a gutter at the base thereof, said conical portion being permeable and having an underlying suction chamber, and said upturned portion having a vertical flange over the 55 edge of which water and slimes overflow, and members operable over the permeable conical surface of the pan having means for progressively moving sands and slimes upwardly thereover and over an unsubmerged 60 portion thereof, the overflow of the pan being in a plane below the plane of the apical portion of the pan and said apical portion of the pan having means for discharging solids.

5. The combination of a circular pan hav-

ing a conical portion and an upturned rim forming a gutter at the base of the cone, said conical portion being permeable and having an underlying suction chamber, and said upturned portion having a vertical 70 flange over which water overflows, and arms operable over the conical surface of the pan having means for progressively moving sands and slimes upwardly thereover and over an unsubmerged portion thereof, said 75 overflow being in a plane below the plane of the apical portion of the cone and the unsubmerged portion of said cone, and said pan having a discharge or opening for solids in its apex.

6. The combination of a circular pan having a conical portion, an upturned rim forming a gutter at the base of the cone, said conical portion being permeable and having an underlying suction chamber, inclined 80 arms arranged substantially parallel with the inclined surface of the pan and having means for progressively moving sands and slimes upwardly thereover and over an unsubmerged portion thereof, said pan having 85 an overflow in a plane below the plane of the apical portion of the cone and below the unsubmerged portion, and having means for discharging solids at the apex, a vertical shaft to which the inner ends of the arms 90 are connected, and means for rotating said shaft to cause the arms to sweep over the 95 conical portion of the pan.

7. The combination of a circular pan having a conical portion, an upturned rim forming a gutter at the base of the cone, said conical portion being permeable and having an underlying suction chamber, an upper and a lower series of inclined arms each having means for progressively moving 100 sands and slimes upwardly over the inclined surface of the pan, one of said series of arms operating over the submerged portion of the pan and the other series of arms operating over the unsubmerged portion of 105 the pan, said pan having a liquid overflow in a plane below the plane of the apical portion of the cone and having means for discharging solids at the apex, shafts to which the arms are connected, and means for rotating 110 said shafts to cause the arms to sweep over the respective conical portions of the pan.

8. The combination of a circular pan having a conical portion, an upturned rim forming a gutter at the base of the cone, said conical portion being permeable and having an underlying suction chamber, an upper and a lower series of inclined arms each having means for progressively moving 120 sands and slimes upwardly over the inclined surface of the pan, one of said series of arms operating over the submerged portion of the pan and the other series of arms operating over the unsubmerged portion of 125 the pan.

- pan, said pan having a liquid overflow in a plane below the plane of the apical portion of the cone and having means for discharging solids at the apex, shafts to which the arms are connected, means for rotating said shafts to cause the arms to sweep over the respective conical portions of the pan, and means rotating the shafts at different speeds.
- 10 9. The combination of a circular pan having a conical portion and an upturned rim forming a gutter at the base of the cone, said conical portion being permeable and having an underlying suction chamber, arms operable over the conical surface of the pan having means for progressively moving sands and slimes upwardly thereover and over an unsubmerged portion thereof, said pan having a discharge opening for solids at its apex and having an overflow for water in a plane below the plane of the apical portion, and means for delivering material to be treated upon the inclined surface of said pan.
- 15 10. The combination of a circular pan having a permeable conical portion and means forming at the base thereof an annular gutter, arms operable over the inclined surface of the pan having means for pro-
- gressively moving sands and slimes upwardly thereover and over an unsubmerged portion thereof, said pan having a suction chamber underlying its permeable portion and having a central discharge for solids and a peripheral overflow for liquid, said overflow being in a plane below the plane of the apical portion of the cone, and means for supplying material to be treated to said pan.
11. The combination of a circular pan having a conical portion and an upturned rim forming a gutter at the base of the cone, said conical portion being permeable and having an underlying suction chamber, and devices operable in a circular path over the permeable portion of the cone, said devices having means for progressively moving the sands and slimes upwardly over the permeable surface of the pan and over an unsubmerged permeable portion thereof, said pan having means for discharging solids at its apex and having a liquid overflow at its periphery lying in a plane below the plane of the apical portion of the cone, and means for directing a reverse current of fluid through the permeable surface of the cone.

In testimony whereof I affix my signature.
WALKER J. BOUDWIN.

It is hereby certified that Letters Patent No. 1,201,014, granted October 10, 1916, upon the application of Walter J. Boudwin, of Salt Lake City, Utah, for an improvement in "Classifiers and Dewaterers," were erroneously issued to The General Engineering Company, of Salt Lake City, Utah, a corporation of Utah, whereas said Letters Patent should have been issued to the inventor, *said Boudwin and The General Engineering Company*, said corporation being owner of *one-half* interest only in said invention, as shown by the records of assignments in this office; and that the said Letters Patent should be read with this correction therein that the same may conform to the record of the case in the Patent Office.

Signed and sealed this 21st day of November, A. D., 1916.

[SEAL.]

F. W. H. CLAY,
Acting Commissioner of Patents.
